United States Patent Office

Des. 193,548
Patented Sept. 11, 1962

193,548

FLOOR PLATE

William A. Stickel, Jr., Franklin Township, Westmoreland County, Pa., assignor to United States Steel Corporation, a corporation of New Jersey

Filed Aug. 18, 1961, Ser. No. 66,397

Term of patent 14 years

(Cl. D13—1)

Fig. 1.

Fig. 2. ← IV

Fig. 4.

Fig. 3.

I claim:

The ornamental design for a floor plate, as shown.
